(57) **CLAIM**

The ornamental design for a steering bezel, as shown and described.

DESCRIPTION

FIG. 1 is a side front, perspective view of our new design;
FIG. 2 is a side front, perspective view of the design of FIG. 1
shown from the side opposite to that of FIG. 1;
FIG. 3 is a side elevational view thereof;
FIG. 4 is a side elevational view from the side opposite to that
of FIG. 3;
FIG. 5 is a front, elevational view thereof; and,
FIG. 6 is a rear elevational view thereof.
The dashed lines of the various figures form no portion of the
claimed design.
